H. L. VENN.
DIE AND HEAD THEREFOR.
APPLICATION FILED APR. 25, 1921.

1,388,177.

Patented June 28, 1921.

Henry L. Venn, Inventor,
By Delos G. Haynes, Attorney.

UNITED STATES PATENT OFFICE.

HENRY L. VENN, OF OAK PARK, ILLINOIS.

DIE AND HEAD THEREFOR.

1,383,177.

Specification of Letters Patent. Patented June 28, 1921.

Application filed April 25, 1921. Serial No. 464,155.

To all whom it may concern:

Be it known that I, HENRY L. VENN, a citizen of the United States, and a resident of Oak Park, county of Cook, State of Illinois, have invented an Improvement in Dies and Heads Therefor, of which the following is a specification.

This invention relates to dies and heads therefor, and with regard to certain more specific features, to a die and head for making parts of rubber tires.

Among the several objects of the invention may be noted the provision of a simple and effective die and head for use with rubber and similar materials; and the provision of an inexpensive and durable construction of die and associated parts, for making parts of rubber tires.

The invention accordingly comprises the features of construction, combinations of elements, and arrangements of parts, which are exemplified in the construction herein-after described and the scope of the application of which will be indicated in the following claims.

In the accompanying drawings, in which is shown one of various possible embodiments of this invention,

Figure 1 is an end elevation of a die and head;

Fig. 2 is an elevation of the other end thereof;

Fig. 3 is a longitudinal vertical section of the die and associated parts;

Fig. 4 is an end elevation of the die plates, on an enlarged scale;

Fig. 5 is a vertical transverse section on the line 5—5 of Fig. 4; and

Fig. 6 is a face view of the disk.

Similar reference characters indicate corresponding parts throughout the several views of the drawings.

Referring now more particularly to Fig. 1 of the accompanying drawings, there is illustrated at 1 the body of a die head, in which is detachably mounted a die member comprising in the present instance two die plates 3, 4, which for convenience may be referred to as the upper and lower plates respectively.

As is indicated in Figs. 3 and 5, these plates are mounted in a horizontal transverse groove 7, in the head member 1. This groove has preferably a moderate amount of taper as is shown in Fig. 1, and the plates

3, 4 are correspondingly tapered, in order to insure a tight fit between plates and head member when the plates are in operative position. Additional means (not shown) may be provided if desired, to hold the plates in position with respect to the head member. Coacting means such as the tongue 9 on the upper plate 3 and the groove 10 on the lower plate 4 prevent displacement of one plate with respect to the other. Or the plates may be made in a single piece.

The head member extends from the flattened end-portion 12 at the groove 7, to an annular portion 14 at the other end of the member. The latter portion is threaded as 16 to fit corresponding threads of the apparatus in which it is mounted, in this instance a cylindrical steam-jacketed casing 18, shown in Fig. 3.

The casing is shown conventionally as having an annular space 20 for the reception of steam for maintaining the rubber in proper condition, and a screw conveyer 22 for forcing the rubber toward and through the die. A disk 24, perforated in two or more places as indicated at 26 in Fig. 6, is mounted between the annular portion of the head member and the adjacent shoulder in the casing 18, and takes the "roll" or "twist" out of the rubber before the rubber reaches the die plates. A belt conveyer 28 is operated at a proper speed to convey the web 29 away from the die plates as fast as it emerges from said plates.

By having the die plates removable, they may be readily replaced when it is found desirable to repair or renew them or to alter the contour of the rubber web that is to be formed in the apparatus.

As is shown in Figs. 1 and 3, the thickness of the head member is substantially the same throughout the several portions exposed to the air. To effect this, the member is formed with the concave or depressed surfaces 31 of a contour similar to the contour of the interior surface 33 (Fig. 3) of the head member. This equality of thickness of metal insures equality of temperature throughout the inner surface 33 and equal radiation of heat from the interior to the exterior, throughout the head member. As a result of this construction, excessive temperature within the member is effectively avoided, and premature curing or hardening of the rubber is prevented.

From the above, it will be seen that the several objects of the invention are realized, and other advantageous results attained.

As various possible embodiments might be made of the above invention and as various changes might be made in the embodiment above set forth, it is to be understood that all matter herein set forth or shown in the accompanying drawings is to be interpreted as illustrative and not in a limiting sense.

I claim:

1. In apparatus of the class described, in combination, a head member, means for detachably securing a die member thereto, means for securing the head member to a casing containing a conveyer, and means for equalizing the heat radiation in the head member.
2. In apparatus of the class described, in combination, a head member of substantially uniform thickness throughout the portions thereof exposed to the air, and a die member detachably secured to the flattened end of said head member.
3. In apparatus of the class described, in combination, a housing, a conveyer therein for forcing material toward the end of the housing, a head member threaded in said end, and a die member detachably secured in said head member and adapted to form the material passing therethrough, into a strip or web of the desired contour, the head member being of substantially uniform thickness throughout.
4. In apparatus of the class described, in combination, a head member of substantially uniform heat-radiating characteristic, and die plates detachably secured to one end of said member.
5. In apparatus of the class described, in combination, a jacketed housing, a conveyer therein for forcing material toward the end of the housing, a member having an annular portion threaded in said end and terminating in a flattened portion, a die member detachably secured in said flattened end of the first member and adapted to form the material passing therethrough, into a strip or web of the desired contour, and a conveyer for removing the web from the first member as the web emerges therefrom, the first member being of substantially uniform thickness throughout, to equalize radiation of heat and to prevent premature curing of the material therein.
6. In apparatus of the class described, in combination, a jacketed housing, a conveyer therein for forcing material toward the end of the housing, a head member having an annular portion threaded in said end and terminating in a flattened portion, coöperating die plates detachably secured together against relative movement and detachably secured in a transverse groove in said flattened portion and adapted to form the material passing therethrough, into a strip or web of the desired contour, an apertured disk mounted between the conveyer and said member and adapted to eliminate the roll or twist of the material fed to the member, and a conveyer for removing the web from the member as the web emerges therefrom, the member being of substantially uniform thickness throughout, to equalize radiation of heat and to prevent premature curing of the material therein.

In testimony whereof, I have signed my name to this specification this 19th day of April, 1921.

HENRY L. VENN.
